UNITED STATES PATENT OFFICE.

ADOLPH F. GALL, OF WEST ORANGE, NEW JERSEY, ASSIGNOR, BY MESNE ASSIGNMENTS, TO NEW JERSEY PATENT COMPANY, OF WEST ORANGE, NEW JERSEY, A CORPORATION OF NEW JERSEY.

PROJECTING APPARATUS.

1,092,906.

Specification of Letters Patent. Patented Apr. 14, 1914.

Application filed April 30, 1912. Serial No. 684,166.

To all whom it may concern:

Be it known that I, ADOLPH F. GALL, a citizen of the United States, and a resident of West Orange, Essex county, New Jersey, 5 have invented certain new and useful Improvements in Projecting Apparatus, of which the following is a description.

My invention relates to projection apparatus and especially to the means for controlling the passage of light through a projection aperture of a lamp house or other means for carrying the source of light.

The object of my invention is the provision of improved means which will insure 10 the closing of the projection aperture of such a device when the latter is in any position other than a projecting position, and which will uncover said aperture when the device is moved into a projecting position.

More specifically described, my invention 15 consists in the provision, in a lamp house or other means having the usual projection aperture and movable on a bed or support into one or more projecting positions, of improved shutter means, the shutter of which means is normally suitably held, preferably by the action of gravity, in a position closing the projection aperture; and in the provision of improved means, preferably positioned on said bed so as to automatically 20 actuate the shutter means to open the shutter when the lamp house or other means having the projection aperture is moved into a projecting position.

Other objects will be disclosed more fully 25 in the following description and appended claims.

In order that my invention may be better understood, attention is directed to the accompanying drawings, forming a part of 30 this specification, in which the same reference characters are used to designate corresponding elements throughout, and in which—

Figure 1 is a view in side elevation showing 35 a lamp house embodying my invention and an operating mechanism for moving and supporting the film, parts being in section; Figs. 2 and 3 are front elevations of the lamp house in different positions on its bed or support; Fig. 4 is a top plan view of 40 a portion of the lamp house, partly in section and Fig. 5 is a plan view of the device

shown in Fig. 1, the lamp house being shown, in full lines, in projecting position 55 with respect to the stereopticon lens, and in dot and dash lines in inoperative position.

Reference character 1 designates the lamp house which is provided in its front wall with the usual projection aperture 2, and 60 which is movably connected to a bed or support 3 in any suitable manner, as by Z-shaped members 4, 4 pivoted both to the bed and the lamp house. A suitable source of light such as a Nernst lamp, shown diagrammatically in Fig. 1, is mounted in the lamp house, and condensing lenses of the usual type are mounted adjacent the projection aperture 2. On the front of the lamp house, in proximity to the projection aperture 2, in the lens tube 2' is a frame 5 in which is slidably mounted a plate 6. The plate 6 has a pair of apertures 7 and 8 adapted to be registered with projection aperture 2 for the projection of motion pictures and stereopticons respectively. Frame 5 is provided with guideways 9 for the reception of lantern slides.

Referring to Figs. 1 and 5, reference character 10 represents the operating mechanism 80 for feeding and supporting the film. On the main frame of the operating mechanism is mounted a lens 17 for the projection of motion pictures and a stereopticon lens 18, with either of which lenses the aperture 2 85 of the lamp house may be operatively aligned by properly moving the lamp house on its bed or support 3. A spring seated ball plunger 11 suitably connected to the lamp house cooperates with indentations 19 provided in a plate 20 secured to the bed 3 to hold the lamp house yieldingly in any one of a plurality of predetermined positions.

For a detailed description of the apparatus described above, reference is made to my 95 co-pending application Serial No. 654,223, filed October 12, 1911.

In order to prevent any possibility of injuring the film or of igniting the same when inflammable film is used, it is desirable that 100 the projection aperture of the lamp house be closed at all times except when it is operatively aligned with either of the lenses 17 and 18 of the operating mechanism 10, and especially when the lamp house is in its 105 rearward position (as shown in dotted lines

in Fig. 5), to permit the film to be threaded through the operating mechanism. To attain this end I provide a shutter 12 suitably supported on the front wall of the lamp house, as by pivot 13, and a rod 14 pivoted to the shutter and depending therefrom and of a length sufficient to extend through an aperture 21 provided in the bottom of the lamp house. The gravity of the parts 12 and 14 is such that the shutter will normally be held against a stop 15 in a position to close the projection aperture 2. On the bed or support 3 is a plurality of cams 16 adapted to coöperate with the end of rod 14 to raise this rod and open shutter 12 when the lamp house is brought into any one of its projecting positions. It will be apparent that when the lamp house is moved out of projecting position, rod 14 will disengage the cam 16 and gravity will act to again close the shutter. The operation of the shutter mechanism is clearly shown in Figs. 2 and 3.

While I have illustrated an embodiment of my invention as applied to the apparatus disclosed in my application referred to above, it will be understood, of course, that it may be readily applied to any lamp house or other means for carrying the source of light mounted so as to be capable of movement into and out of one or more projecting positions.

Having clearly set forth the nature of my invention and shown and specifically described one embodiment thereof, what I claim and desire to protect by Letters Patent is:

1. The combination with a lamp house having a projection aperture and adapted to be moved into and out of a projecting position, of means adapted to operate automatically to open and close said aperture when the lamp house is moved into and out of projecting position respectively, substantially as described.

2. The combination with a lamp house having a projection aperture and adapted to be moved into and out of a plurality of projecting positions, of means comprising a shutter adapted to operate automatically to open and close said aperture when the lamp house is moved into and out of any of the projecting positions respectively, substantially as described.

3. The combination with a lamp house having a projection aperture and adapted to be moved into and out of a projecting position, of means comprising a shutter normally closing said aperture, and means adapted automatically to actuate said first means to open said shutter when the lamp house is moved into projecting position, substantially as described.

4. The combination with a lamp house having a projection aperture and adapted

to be moved into and out of a plurality of projecting positions, of means comprising a shutter normally closing said aperture, and means adapted automatically to actuate said first means to open said shutter when the lamp house is moved into any of the projecting positions, substantially as described. 70

5. The combination of a lamp house having a projection aperture, of a bed, means connecting the lamp house to said bed, but permitting said lamp house to be moved relatively thereto, whereby the lamp house may be moved into and out of a projecting position, means comprising a shutter normally closing said aperture, and means on said bed adapted automatically to actuate said second named means to open said shutter when the lamp house is moved into projecting position, substantially as described. 75 80

6. The combination with a lamp house having a projection aperture, of a bed, means connecting the lamp house to said bed, but permitting said lamp house to be moved relatively thereto, whereby the lamp house 90 may be moved into and out of any one of a plurality of projecting positions, means comprising a shutter normally closing said aperture, and means on said bed adapted automatically to actuate said second named 95 means to open said shutter when the lamp house is moved into any of the projecting positions, substantially as described. 85

7. In an apparatus of the class described, a bed or support, a lamp house having a projection aperture and movably connected to said bed or support whereby said lamp house may be moved into and out of a projecting position, means comprising a shutter normally closing said aperture, and a cam on said bed or support adapted automatically to actuate said means to open said shutter when the lamp house is moved into projecting position, substantially as described. 100

8. In an apparatus of the class described, a bed or support, a lamp house having a projection aperture and movably connected to said bed or support, whereby said lamp house may be moved into and out of a plurality of projecting positions, means comprising a shutter normally closing said aperture, and means comprising a plurality of cams on said bed or support adapted automatically to actuate said first means to open said shutter when the lamp house is moved into any projecting position, substantially as described. 110 115

9. The combination with a lamp house having a projection aperture, of a bed, means pivotally connecting the lamp house to said bed whereby the lamp house may be moved into and out of a projecting position, means comprising a shutter and a rod depending therefrom for normally closing said aperture, and a cam on said bed adapted to 120 125 130

- actuate said rod to open said shutter, when the lamp house is moved into projecting position, substantially as described.
10. The combination with a lamp house having a projection aperture, of a bed, means pivotally connecting the lamp house to said bed whereby the lamp house may be moved into and out of a plurality of projecting positions, means comprising a shutter and a rod depending therefrom for normally closing said aperture, and means comprising a plurality of cams on said bed adapted to actuate said rod to open said shutter, when the lamp house is moved into any projecting position, substantially as described.
11. The combination with a film operating mechanism having a picture projecting lens, of a bed, a lamp house having a projection aperture and movably connected with said bed, whereby the lamp house may be moved into and out of a position in which said projection aperture and said lens are operatively aligned, means comprising a shutter for closing said aperture when the aperture and lens are out of operative alignment, and means on said bed adapted, automatically to actuate said first means to open said shutter when the lamp house is moved to a position in which said aperture and lens are operatively aligned, substantially as described.
12. The combination with a device provided with a projection aperture and adapted to be moved into and out of a projecting position, of a source of light carried by said device, and means adapted to operate automatically to open and close said aperture when said device is moved into and out of projecting position respectively, substantially as described.
13. The combination with a device provided with a projection aperture and adapted to be moved into and out of a plurality of projecting positions, of a source of light car-
- ried by said device, and means adapted to operate automatically to open and close said aperture when said device is moved into and out of any projecting position respectively, substantially as described.
14. The combination with a projecting device having a projection aperture and adapted to be moved into and out of a projecting position, of means adapted to operate automatically to close said aperture when the projecting device is moved out of projecting position, substantially as described.
15. The combination with a projecting device having a projection aperture and adapted to be moved into and out of a plurality of projecting positions, of means adapted to operate automatically to close said aperture when the projecting device is moved out of any of the projecting positions, substantially as described.
16. The combination with a projecting device having a projection aperture and adapted to be moved into and out of a projecting position, of means comprising a member for closing said aperture and adapted to operate automatically to open said aperture when the projecting device is moved into projecting position, substantially as described.
17. The combination with a projecting device having a projection aperture and adapted to be moved into and out of a plurality of projecting positions, of means comprising a member for closing said aperture and adapted to operate automatically to open said aperture when the projecting device is moved into any of the projecting positions, substantially as described.

This specification signed and witnessed this 29th day of April 1912.

Copies of this patent may be obtained for five cents each, by addressing the "Commissioner of Patents, Washington, D. C."

It is hereby certified that in Letters Patent No. 1,092,906, granted April 14, 1914, upon the application of Adolph F. Gall, of West Orange, New Jersey, for an improvement in "Projecting Apparatus," errors appear in the printed specification requiring correction as follows: Page 1, line 69, after the reference-numeral "2" insert the words and reference-numeral *in the lens tube 2'*; same page, line 71, strike out the words and reference numeral "in the lens tube 2"; and that the said Letters Patent should be read with these corrections therein that the same may conform to the record of the case in the Patent Office.

Signed and sealed this 12th day of May, A. D., 1914.

[SEAL.]

J. T. NEWTON,

Commissioner of Patents.
